UNITED STATES PATENT OFFICE

2,009,148

LAY MOTION FOR LOOMS

Oscar V. Payne, Worcester, Mass., assignor to
 Crompton & Knowles Loom Works, Worcester,
 Mass., a corporation of Massachusetts

Application April 16, 1931, Serial No. 530,565

4 Claims. (Cl. 139—190)

This invention relates to improvements in lay motions for looms and it is the general object of the invention to provide an improved drive for the lays of long looms.

5 In certain types of looms which weave fabrics several hundred inches in width the torque or twist of revolving shafts is such as to interfere seriously with the proper motions of the lay. It has been proposed heretofore to cause forward movement of long lays by placing a driving member under tension and connecting it to the lay at a plurality of points. It is an important object of my invention to provide in connection with this type of lay motion an improved means 10 for moving the lay rearwardly by a positive motion so as to insure an increased dwell for the flight of the shuttle. In this connection it is desirable to allow the lay to remain at rest in its rearward position while the shuttle is in flight.

15 20 In previously proposed constructions of this type it has been customary to store energy in a spring or similar device as the lay is beating-up, this energy being used to return the lay to its rearward position. In such a construction the driving parts on the lay are called upon to provide energy for the forward and also the rearward movement of the lay at the same time, thereby increasing the strain of the parts and the maximum power requirement. It is an important object of my present invention to provide means 25 for moving the lay forwardly in a positive manner and also rearwardly by positive connections, the forces to accomplish the back and forth motion of the lay being derived from the loom successively instead of simultaneously.

30 With these and other objects in view which will appear as the description proceeds, my invention resides in the combination and arrangement of parts hereinafter described and set forth in the 35 claims.

40 In the accompanying drawing, wherein a convenient embodiment of my invention is set forth,

Fig. 1 is a top plan view of a portion of a loom having my invention applied thereto,

45 Fig. 2 is a front elevation showing certain parts of the structure set forth in Fig. 1,

Fig. 3 is an end elevation taken in the direction of arrow 3, Fig. 2,

50 Fig. 4 is a detailed vertical section on line 4—4 of Fig. 1,

Fig. 5 is a detailed section on line 5—5 of Fig. 1, and

Fig. 6 is a horizontal section on line 6—6 of Fig. 3.

55 Referring to the drawing, I have shown a loom

frame 10 having a breast beam 11 and a lay 12. The latter carries a reed 13 and may be supported in any approved manner so as to be movable toward and from the breast beam. A plurality of forwardly extending links 15 are pivotally connected to the lay, the rear end of each link being movable about a vertical lay carried pivot pin 16. The forward end of each link is connected as at 17 to a bell crank lever 18. Each bell crank lever is pivoted about a vertical stud 19 fixed with respect to the breast beam 11. A transverse driving rod 20 extending preferably over and along the breast beam and under the cloth has connection with each of the bell crank levers at points designated herein at 21.

10 The bar 20 may be connected by a link 22 to the upper end of a lever 23. The latter is pivoted as at 24 at the lower end thereof to a fixed stand 25. A cam 26 secured to a revolving shaft 27 has a dwell surface 28 and an inclined rise and fall surface 29. A roll 30 as shown in Fig. 6 is supported by a stud 31 which bridges a forked part of the lever 23, and engages cam 26 as the latter rotates.

15 By means of the matter thus far described reciprocations of the bar 20 are either caused or permitted by the cam 26. This structure may be substantially the same as that shown in patent to Wilson No. 1,415,286, the lay being moved forwardly by a positive movement derived from the lower part of cam face 29 as viewed in Fig. 2 with the cam rotating in the direction of arrow A.

20 My invention relates more particularly to means for causing the backward movement of the lay after the latter has beaten in weft, and in carrying my invention into effect I provide a second lever 40 movable about a fixed pivotal support 41 carried by the stand 25a. Lever 40 is provided with a roll 42, similar to roll 30, to engage a cam 43 which has a dwell 44 and a recess 45.

25 The lower end of the lever is attached by means of a connector 46 to a cable or other tension member designated herein at 47. The latter extends across the loom and has pivotal connection as at 48 with the lower end of rocking lever 49. The latter is mounted for oscillation on a fixed stud 50 supported by a stand 51. The upper end of lever 49 may be attached by means of an adjustable connector 52 to the right hand end of the bar 20, as indicated in Figs. 1 and 2.

30 When the shaft 27 rotates the inclined conjugate surfaces 29 and 45 will have such relation with their respective rollers that the upper 55

end of lever 23 moves to the left at the same rate as the upper end of lever 49. It is not necessary that these amounts be the same, but it is desirable not to set up strains in the bar 20.

- 5 By the operation of the structure set forth herein the levers operate as a pair and may be considered as yoked together with their connections maintaining a substantially closed system of forces for moving the lay. The cam 26 and its lever 23 produces the forward movement of the lay, while the cam 43 together with its lever 40 accomplishing the rearward movement. The power in both instances is transmitted through the system of bell crank levers and the cams operate to transmit power from the shaft 27 to the lay in successive impulses, the rising part of the cam 29 effecting the forward movement of the lay, after which the rising part of cam 45 will effect rearward movement of the lay. In 10 this way the shaft 27 is never called upon to supply more force than that which is required to move the lay in one direction. Furthermore, the positive connections through the cable or tension mechanism 47 permits a rapid rearward movement of the lay so that the dwell during which the shuttle may be in flight can be increased. The effect of this is to permit a faster running of the loom without depriving the shuttle of sufficient time to get across the loom.
- 15 30 Those parts of the cam inclines which lie within the same angle with reference to the axis of shaft 27 are related so that the rod 20 has a measured motion at both ends. This result is attained herein by having the actuating cam levers of equal throw and pivoting the lever 49 at its center. By this arrangement one cam lever moves in one direction by an amount equal to the opposite movement of the other cam lever in the same time.
- 20 35 40 45 50 40 By means of the mechanism described I have provided a lay motion wherein two cams operate in conjunction to reciprocate the lay, each cam giving a motion which is the complement of the other cam so that as one cam operates to require the lay to move forwardly for instance the other cam will relinquish its control to permit such forward motion. Both cams will ordinarily be operatively related to the lay as the latter moves backwardly or forwardly, and each cam will have one part to move the rod 20 in one direction and another part to permit movement of the rod in the opposite direction.

Having thus described my invention it will be seen that changes and modifications may be made therein by those skilled in the art without departing from the spirit and scope of the invention and I do not wish to be limited to the details herein disclosed, but what I claim is:

1. In a loom having a lay, a pair of oppositely reciprocating conjugate cams at one end of the loom, a rocking lever at the other end of the loom, a lay driving rod connecting one of the conjugate cams and the rocking lever, operative connections between the rod and the lay, and return connections between the other conjugate cam and the rocking lever, said rocking lever and rod being responsive to the movement of the conjugate cams and moving positively in opposite directions to move the lay positively forwardly and backwardly.
2. In a loom having a lay, a single reciprocating member extending along the lay, operative connections between the member and the lay, a rocking lever at one end of the loom connected to one end of said member, and a pair of oppositely moving actuating levers at the other end of the loom, one of said actuating levers being connected to the other end of said reciprocating member and the other lever being operatively connected to the rocking lever, one of said actuating levers imparting a positive movement to the reciprocating member directly and the other actuating member imparting positive movement to said member in the opposite direction by a force transmitted through the rocking lever.
3. In a loom having a lay, a pair of oppositely reciprocating members extending substantially parallel to the lay, operating connections between one of said members and the lay, means to connect said members at one end of the loom, and means to impart force to said members at the other end of the loom effective to give said members alternate positive movements.
4. In a loom having a lay, a pair of members extending substantially parallel to the lay, operating connections between one of said members and the lay, means to connect the ends of the members adjacent one end of the loom to cause said members to reciprocate in opposite directions, and an actuating lever for each member at the other end of the loom.

50 OSCAR V. PAYNE.
